EXTENSION BRACKET FOR HOSPITAL BEDS

Joe J. Ettinger, Warsaw, Ind., assignor to Zimmer Manufacturing Company, Warsaw, Ind.

Application May 29, 1950, Serial No. 164,953

1 Claim. (Cl. 128—84)

This invention relates to extension brackets for the ends of beds such as are used in hospitals and elsewhere for surgical cases involving fractures and the like in which it is desirable to exert traction on a part of the patient's body.

One important object of the invention is to provide a novel and improved form of extension bracket adapted to be supported from the cross rail of a bed foot or head and there securely located without the use of clamps or other than the suspension means.

A second important object of this invention is to provide an extension bracket for the purpose set forth wherein novel means are provided for permitting vertical adjustment of the bracket parts and for holding them securely in adjusted position.

A third important object of the invention is to provide a novel device of the kind described wherein the adjustable part may be arranged in either erect or inverted position as for tension on the lower extremities in erect position or for producing tension of the cervical vertebrae in inverted position.

With the above and other objects in view, as will be presently apparent, the invention consists in general of certain arrangements of details and combinations of parts hereinafter fully described, illustrated in the accompanying drawings and particularly claimed.

In the drawings like characters of reference indicate like parts in the several views, and:

Fig. 1 is a perspective view showing the invention as applied to the foot of the partially illustrated bed and used in connection with traction means extending from a leg of a patient.

Fig. 2 is a side elevation of the invention with the adjustable portion inverted as in applying cervical traction.

Fig. 3 is a front elevation of the device in the position shown in Fig. 1.

Fig. 4 is a section on the line 4—4 of Fig. 3.

In the embodiment of the invention as here illustrated there is provided a support or hanger consisting of a stout metal rod having a horizontally disposed portion 10 from the ends of which rise the vertical arms 11. These arms 11 have their upper ends bent rearwardly to form inverted semi-circular bends 12, the arms thus being of inverted J-shape. These arms are, in use, hooked over the top rail A of a bed end and, for the purpose of preventing injury to the finish of the bed, are provided with tubular rubber coverings 13. Also the portion 10 of the de-

vice is provided with tubular rubber covers 14 for like purposes.

Welded or otherwise securely fixed to the portion 10 is a vertical guide member 15 having an opening 16 extending vertically therethrough, this opening being preferably rectangular in cross section. Slidably mounted in the opening 16 is a bar 15 also preferably rectangular in cross section. However, any cross section of opening and bar may be employed, it being sufficient that the bar is non-rotatable in the guide 15. The bar is thus vertically adjustable in the guide and, in order to secure it in adjusted position, a handle provided setscrew 17 is screwed through the front wall of the guide 15 to engage the bar 16. The bar 16 has an alined extension 18 bifurcated at its extremity as at 19 to provide space for a grooved pulley 20 mounted on a shaft or pin 21 which spans the bifurcation 20 and has ends projecting laterally from the extension. Projecting horizontally from the extension 18 at its junction with the bar 16 is a pair of laterally spaced arms 22 secured by a rivet 23. Through the free ends of the arms 22 extends a shaft or pin 24 on which, between the shafts 21 and 24 is a pair of diagonal braces 26. Secured on the shafts 21 and 24 is a pair of diagonal braces 26.

In this construction the frame having the arms 11 and guide 15 constitute a support to carry 30 adjustably a bracket formed by the bar 16, its extension 18 and the arms 22 and 26.

In use when traction is desired for a lower extremity a cord or wire B is led, with the bracket in erect position as in Fig. 1, over the pulleys 20 and 25 and has one end connected to the lower extremity as at C while its other end carries a weight D. For cervical traction the bracket is arranged in inverted position as shown in Fig. 2 so that the cord or wire extends close to the mattress of the bed and passes only over the pulley 25. Obviously in either position the bracket may be adjusted vertically and there held by the screw 17.

What is claimed is:

In an extension apparatus for surgical fracture beds, a pair of inverted J-shaped members, a cross-bar extending between and rigidly connecting said members, a tubular guide rigidly fixed to said cross-bar, said guide extending 45 parallel to said members and having an opening axially therethrough of polygonal cross section, an adjustable bar fitting slidably in said guide and conforming in cross section to the opening 50 therein, means in the guide to secure said bar in adjusted position and pulley carrying means 55 in adjusted position and pulley carrying means

at one end of said adjustable bar, said last means comprising a pair of spaced members projecting upwardly from the upper end of said adjustable bar, said last mentioned means further including spaced members projecting at right angles from said adjustable bar, brace members connecting the outer ends of the last mentioned members and the upper ends of the next to last mentioned members and pulleys supported between the bars extending from the adjustable bar at their junction to said braces. 10
